UNITED STATES PATENT OFFICE.

JOHN ANTONIO MESSINA AND CHARLES S. B. MOFFAT, OF KEY WEST,
FLORIDA.

LAMP-CHIMNEY CLEANER.

SPECIFICATION forming part of Letters Patent No. 453,316, dated June 2, 1891.

Application filed October 22, 1890. Serial No. 368,909. (No model.)

To all whom it may concern:

Be it known that we, JOHN ANTONIO MESSINA and CHARLES S. B. MOFFAT citizens of the United States, residing at Key West, in 5 the county of Monroe and State of Florida, have invented a new and useful Lamp-Chimney Cleaner, of which the following is a specification.

The invention relates to improvements in 10 lamp-chimney cleaners.

The object of the present invention is to provide a simple and inexpensive device adapted to be readily inserted into a lamp-chimney and expanded and to conform to the 15 configuration of a chimney when it is expanded.

The invention consists in the construction and novel combination and the arrangement of parts hereinafter fully described, illustrated 20 in the accompanying drawings, and pointed out in the claims hereto appended.

In the drawings, Figure 1 is a perspective view of a lamp-chimney cleaner constructed in accordance with this invention and provided with a cloth cover or bag. Fig. 2 is a similar view, the cover or bag being removed and the lamp-chimney cleaner being expanded. Fig. 3 is a longitudinal sectional view. Fig. 4 is a transverse sectional view.

Referring to the accompanying drawings, 1 designates a stem or rod, provided at one end with a handle 2 and having at the other end a cap or knob 3 and a ring 4, provided with a circumferential groove 5 and a series of recesses 6 in its circumference and having arranged in the recesses perforated ends 7 of curved spreader-arms 8, which are secured to the ring 4 by a wire 9, arranged in the groove 5 and passing through the perforations of 35 the ends 7. The curved spreader-arms 8 are provided near their outer ends with eyes 10, which are arranged on the inner faces of the arms, and to which are secured bifurcated ends 11 of rods 12, which have their other ends se-

cured in recesses 13 in the circumferential annular flange 14, arranged at the upper end of a sliding sleeve 15, and provided with a circumferential groove, in which is secured a wire 16, that fastens the rods 12 to the flange. 40 The sleeve 15 is capable of longitudinal move-

ment on the stem or rod 1 to bring the rods 12 approximately perpendicular to the spreader-arms to expand the latter and to arrange the rods 12 along the stem to close or contract the spreader-arms. The longitudinally-moving 55 sleeve is provided with a slot 17, extending longitudinally of it and receiving a projection 18 of the stem 1 to prevent the sleeve turning thereon. The curved spreader-arms are constructed of thin sheet metal, preferably steel, 60 and are slightly transversely concaved, and are longitudinally curved similarly to the ordinary lamp-chimney from their upper or hinged ends to their lower or outer ends, and the said spreader-arms are adapted to be expanded within a chimney and conform to the configuration of the same to press or force in contact with the chimney a cloth bag 20, preferably constructed with canton-flannel to remove grease and smoke and other products 65 of combustion. The canton-flannel bag is padded at 22 with cotton or the like to give elasticity and prevent injury to a chimney.

The spreader-arms consist of the metal body and a cloth or felt covering or exterior 23, 75 and they are arranged in a circular series around the stem, and when they are closed they entirely surround and inclose the upper portion of the stem. The end 24 of the sleeve is provided with oppositely curved finger-holds 25, which enable the sleeve to be readily moved for operating the device, and the said sleeve is provided intermediate of its ends with a ring 26, secured to the sleeve by radial arms 27, and the said ring is adapted to have 80 the open ends of the bag or cover drawn around it, and thereby secure and properly hold on the chimney-cleaner, as illustrated in Fig. 1 of the accompanying drawings.

From the foregoing description and the accompanying drawings the construction, operation, and advantages of the invention will be readily understood.

What we claim is—

1. In a chimney-cleaner, the combination of 95 the stem, the rigid spreader-arms curved throughout their length and conforming to the configuration of a chimney and hinged to the stem, the sliding sleeve arranged on the stem, and the rods pivotally connecting the 100

arms and the sleeve, substantially as described.

2. In a chimney-cleaner, the combination of the stem, the rigid spreader-arms hinged to the stem and consisting of the metal body 5 and a felt exterior, the sliding sleeve arranged on the stem, and the rods pivotally connecting the spreader-arms and the sleeve, substantially as described.

10 3. In a chimney-cleaner, the combination of the stem, the spreader-arms hinged to the stem, the sleeve sliding on the stem and provided with a ring 26, the rods pivotally connected to the sleeve and the spreader-arms,

the fabric bag having its open end drawn over and secured at the ring and provided intermediate its ends with a padded portion 22, and the oppositely-disposed curved finger-holds extending from the stem, substantially as described. 20

In testimony that we claim the foregoing as our own we have hereto affixed our signatures in presence of two witnesses.

JOHN ANTONIO MESSINA.

CHARLES S. B. MOFFAT.
